UNITED STATES PATENT OFFICE.

GEORGE SABELMAN, OF PROBERTA, CALIFORNIA.

NAILING-MACHINE.

1,146,105.

Specification of Letters Patent. Patented July 13, 1915.

Application filed July 21, 1914. Serial No. 852,187.

To all whom it may concern:

Be it known that I, GEORGE SABELMAN, a citizen of the United States, residing at Proberta, in the county of Tehama and 5 State of California, have invented new and useful Improvements in Nailing-Machines, of which the following is a specification.

The object of the present invention is to provide a machine which will facilitate nailing. It is especially useful where a large 10 number of nails have to be inserted in rapid succession, as in shingling.

In the accompanying drawing, Figure 1 is a side view of the machine; Fig. 2 is an 15 enlarged longitudinal vertical section of a portion thereof; Fig. 3 is a transverse vertical section; Fig. 4 is a horizontal section on the line 4-4 of Fig. 3.

Referring to the drawing, 1 indicates a 20 tube, partly supported upon two legs 2, riveted to the tube. On one terminal portion of the tube is supported a magazine 3 for nails.

In the underside of the tube there extends 25 from the lower side of the magazine to the lower end of the tube a slot 4, sufficiently wide to permit the body of a nail 5 to pass therethrough, while the head 10 of the nail is retained within the tube. A gate 15, ad- 30 justed by a handle 25, is provided, which allows to pass only those nails whose stems extend through the slot 4 in the tube. The lower end of said tube is extended to form two vertical walls between which is secured 35 the upper portion of a block 6. To the lower portion of said block, which is re- duced in thickness, is secured by screws 7 a second block 8, between which and the block 6 is a third block 9. Said third block is se- 40 cured in place by a lower screw 11 passed through the blocks 6 and 9 and screwed into the block 8, and also by an upper screw 12 passed through the block 6 and screwed into the block 9, the upper ends of the blocks 8 45 and 9 being slightly lower than the lower end of the slot 4. When secured in place there is a passage 13 between the blocks 8 and 9 sufficiently wide for the body of a nail to pass therethrough, said passage extending, 50 first, longitudinally, and then transversely, or toward the block 6.

The head of the nail at first slides upon the upper ends of the blocks 8 and 9, part on each, and as the body of the nail turns the 55 corner, from the longitudinal to the trans- verse portion of the passage, the head of the

nail moves off the tops of the blocks 8 and 9 and slides down sloping surfaces 14, 16, re- spectively on the blocks 8 and 9, said sur- faces sloping downward and meeting the 60 transverse portion of the passage 13, so that, as the nail descends, its head 10 is partly received in a vertical groove 17 in the inner face of the block 6. At this point the descent of the nail is arrested by a lever 18 65 actuated by a spring 20 and extending through a vertical slot 19 terminating in said groove 17, and abutting against the body of the nail beneath the head, said body being still contained in the transverse por- 70 tion of the passage 13. In a cylindrical hole 22 forming an upper extension of said groove 17 can slide a cylindrical bolt 23 having a grooved head 24, and engaging said groove in said head is a wire spring 26 75 secured upon the top of the tube 1 by plates 25 secured by screws to said tube, the up- ward movement of said spring 26 being lim- ited by a looped portion 27 thereof passing over and around the spring 26. If a blow 80 be given by a hammer to the head of said bolt, said bolt descends in said hole 22, and the lower end thereof impinges upon one side of the head of the nail, which is at this time extending into said groove 17, and 85 depresses the nail, forcing out the lever 18. The bottom 28 of the transverse portion of the passage slopes downwardly toward the block 6, so that, if the point of the nail still remains in said passage as it descends, said 90 point is finally forced out of said passage into the groove 17, into vertical alinement with the head, and, when the point of the nail passes out of the lower end of said pas- 95 sage, it has assumed an accurately vertical position. By reason of the sloping surfaces 14, 16 the head is also moved from the blocks 8 and 9 almost entirely into the groove 17 in the block 6, so as to be completely under the end of the bolt, so that, in the final mo- 100 tion of the nail under the action of the bolt, it moves in perfect alinement with the bolt. The spring 26 immediately raises the bolt to its normal position after the blow by the hammer, and the lever 18 returns under the 105 action of its spring 20. The spring-actuated lever 18 performs the very necessary func- tion of holding the first nail in such a pos- 110 sition that its head, abutting against the stem of the next succeeding nail, maintains the head of the latter outside of the path of the bolt in its descent.

Secured to the upper portion of the block 6 and extending over the head of the nail before said head passes over the tops of the blocks 8 and 9 is a stop 29 which automatically arrests the head of any nail in the lower portion of the slot, if at too high a level to properly pass over the tops of the blocks 8 and 9. Secured to the under side of the tube, one on each side of the slot 4, 10 are guide plates 30, which guide the nail accurately into the longitudinal portion of the passage 13.

I claim:—

15 A nailing machine comprising a slotted tube down which the nails can travel, a passage-way at the lower end of said tube of sufficient width for the greater part of its height to receive only the body of a nail, the first portion of said passage-way being 20 in the same vertical plane as said tube, and

the latter portion being in a vertical plane making an angle with that of the tube, a vertical guideway into which the latter portion of the passage-way leads, the bottom of said latter portion sloping downward into 25 said guideway, a bolt in said guideway having an exposed head, and spring-controlled means for upholding a nail in such position in said guideway that its head will arrest the next succeeding nail in said passage-way 30 at a point at which its head is outside the path of the bolt.

In testimony whereof I have hereunto set my hand in the presence of two subscribing witnesses.

GEORGE SABELMAN.
